UNITED STATES PATENT OFFICE.

JOHN F. CONWAY, OF PHILADELPHIA, PENNSYLVANIA.

UMBRELLA AND WATER-COOLER STAND.

SPECIFICATION forming part of Letters Patent No. 237,488, dated February 8, 1881.

Application filed May 24, 1880. (No model.)

To all whom it may concern:

Be it known that I, JOHN F. CONWAY, of Philadelphia, in the county of Philadelphia, in the State of Pennsylvania, have invented 5 Improvements in Umbrella and Water-Cooler Stands, of which the following is a specification, reference being had to the accompanying drawings, wherein—

Figure 1 is a perspective of umbrella-stand; 10 Fig. 2, a perspective of water-cooler stand, and Fig. 3 a vertical section of the water-cooler stand, enlarged.

My invention has for its object to provide a fixture or device capable of use alternately 15 as an umbrella and a water-cooler stand.

My invention consists in the combination, with a peculiarly-constructed umbrella-stand, having a detachable top, affording a rest for a water-cooler, of a cup-support and drip-re- 20 ceiver, all as hereinafter described and claimed.

Referring to the accompanying drawings, Fig. 1 indicates an umbrella-stand consisting of the ring A, supported on legs B B, between which latter is fastened a pan or like vessel, 25 C, for receiving the drip from umbrellas.

Fig. 2 represents said stand converted into a stand for a water-cooler. This is accomplished by fitting over the ring A a metallic top, D, having an annular flange, d, for embracing 30 said ring, or other equivalent means of attach-

ing said top in position on said ring. Said top may have the cup-support and drainer (shown at E) formed integral with it, and I have so shown it; but I do not limit my invention to the top D and support E made in one piece, as 35 they may be separate.

The support E forms, also, a receiver for the drip from the faucet of the water-cooler and a drainer for the cup. To carry off the drip from said support a tube, e, is provided, running 40 from its bottom through one of the legs B to a detachable pipe, F, which leads to the pan C. The top, with its tube and pipe, may, in a moment, be applied to the umbrella-stand and as readily removed, accordingly as the stand 45 may be desired for umbrellas or for a cooler.

What I claim as my invention is—

The combination, with an umbrella-stand composed of parts A B C, of a detachable top affording a rest for a water-cooler and a cup- 50 support and drip-receiver, E, substantially as shown and described.

In testimony that I claim the foregoing I have hereunto set my hand this 22d day of May, 1880.

JOHN F. CONWAY.
